CLAIM

We claim the ornamental design for a vehicle roof, as shown and described.

DESCRIPTION

FIG. 1 is a perspective view of the vehicle roof showing our new design; and,

FIG. 2 is a left side elevational view thereof; the right side elevational view being a mirror image thereof.

All portions of the vehicle roof not shown form no part of the claimed design.

1 Claim, 2 Drawing Sheets

FIG. 1

FIG. 2
